(57) **CLAIM**

The ornamental design for a setting plate for cluster set of stones, as shown and described.

DESCRIPTION

FIG. 1 is a perspective view of a setting plate for cluster set of stones showing my new design.

FIG. 2 is a top plan view thereof.

FIG. 3 is a bottom plan view thereof.

FIG. 4 is a right side elevation view thereof.

FIG. 5 is a left side elevation view thereof.

FIG. 6 is a front elevation view thereof; and,

FIG. 7 is a rear elevation view thereof.

The broken lines in the drawings illustrate portions of the setting plate for cluster set of stones that form no part of the claimed design.

1 Claim, 5 Drawing Sheets
